STOCK INLET

Francis A. Helin, Watertown, N. Y., assignor to
 The Bagley and Sewall Company, Watertown,
 N. Y., a corporation of New York

Application May 8, 1943, Serial No. 486,203

14 Claims. (Cl. 92—44)

This invention relates to stock inlets for paper making machines characterized by simplicity, compactness and maintenance of continual flow of stock from the time it leaves the stock chest or reservoir until it is deposited on the forming surface of the paper making machine.

More specifically the invention relates to a stock inlet having a stock spreader chamber receiving stock directly from a delivery pipe and spreading it across the width of a paper making machine together with an inlet chamber extending across the width of the forming surface of a paper machine and receiving stock in controlled amounts from the spreader chamber.

In accordance with this invention, a stock spreader chamber composed of a closed ended pipe is horizontally mounted across the width of a Fourdrinier type paper making machine immediately in advance of the breast roll end of such a machine. The pipe is mounted on upright pedestals or end frames.

A stock delivery pipe connects the conventional stock chest or reservoir with the central portion of the horizontally mounted pipe. A stock return pipe is also provided for returning excess amounts of stock back to the stock chest. A bypass valve is interposed between the horizontal pipe, the stock delivery pipe, and the stock return pipe to divert the flow of paper stock back to the stock chest.

The horizontal pipe is connected through laterally extending valved pipes spaced along the length thereof with an inlet chamber. This inlet chamber is composed of a second horizontal closed ended pipe suspended from the end frames over the upper run of the forming wire of the paper machine. This second pipe has a slot therethrough along the length thereof. A nozzle projects from this second pipe and provides a passageway for stock discharged through the slot in the pipe. The nozzle preferably has an adjustable or flexible upper lip to control the velocity and uniformity of stock delivery to the forming wire.

If desired a flow evener roll can be rotatably mounted in the second horizontal pipe immediately in front of the slot to break up fiber bundles and to prevent formation of eddy currents in the stock.

The end frames supporting the inlet of this invention are preferably equipped with cylindrical chambers slidably receiving pistons acting on the parts normally supported by the frame. Fluid under pressure can be introduced into these cylindrical chambers for raising the pistons and

thereby lifting the horizontal pipes relative to the paper machine forming wire. This will facilitate changing of the forming wire. Pipe connections with the horizontal pipes that are not raised with the horizontal pipes can be equipped with quick disconnect coupling devices.

A feature of the invention includes an equalizer shaft connected through cranks and levers with the end portions of the inlet chamber. This equalizer shaft prevents one piston from working ahead of the other piston when raising or lowering the structure since, in such event, the shaft will be subjected to a torsional twist and will effectively resist unequal movements of the pistons.

It is, then, an object of this invention to provide a compact light weight stock inlet for paper making machines which distributes stock uniformly across the width of the machine without permitting the formation of quiescent stock areas.

A further object of the invention is to provide a stock inlet having a stock spreader chamber for spreading stock from a delivery pipe across the width of a paper machine together with a stock inlet chamber disposed across the width of the forming surface of a paper machine and receiving stock from the spreader chamber uniformly along its length through a plurality of valved passages connecting the two chambers and controllable for even distribution of stock from the spreader chamber uniformly along the length of the inlet chamber.

A still further object of the invention is to provide a stock inlet with a fluid pressure actuated lift for raising the inlet to facilitate the changing of a forming wire on a paper machine.

A still further object of the invention is to provide a stock inlet wherein stock is continually flowed through a delivery pipe into a closed ended horizontal spreader pipe, is then discharged in controlled amounts along the length of this spreader pipe into a second closed ended horizontal pipe and is then discharged onto a forming surface of a paper machine along the length of this second pipe.

A still further object of the invention is to provide a self-draining stock inlet eliminating wastage of stock.

A still further object of the invention is to provide an improved by-pass valve construction for stock flow control.

Another object of the invention is to provide a hydraulic lift for a stock inlet wherein the movements of the pistons are held in synchronized relation through an equalizer shaft.

A still further object of the invention is to pro-

vide a flexible lip for a stock inlet controlled along its entire length by a master control mechanism and having a plurality of individually operated toggle-controls for flexing localized increments of the lip.

A general object of the invention is to provide a stock inlet having readily operated and easily accessible controls and composed of light-weight parts in compact relationship.

Other and further objects of the invention will be apparent to those skilled in the art from the following detailed description of the annexed sheets of drawings which illustrate preferred embodiments of the invention by way of example only.

On the drawings:

Figure 1 is a somewhat diagrammatic fragmentary and broken side elevational view, with parts in vertical cross section, of a stock inlet according to this invention illustrating one manner in which the inlet is adapted to be used on a Fourdrinier type paper making machine.

Figure 2 is a view similar to Figure 1 illustrating another arrangement of the stock inlet of this invention relative to the paper making machine and associated stock reservoirs.

Figure 3 is a rear side elevational view of the stock inlet according to this invention.

Figure 4 is a top plan view of the stock inlet according to this invention and also illustrating the relationship of the inlet relative to the forming wire of a paper making machine.

Figure 5 is a vertical cross-sectional view with parts in elevation, taken along the line V—V of Figure 4.

Figure 6 is a view similar to Figure 5 illustrating the inlet in raised position to facilitate changing of the forming wire of the paper machine.

Figure 7 is a vertical cross-sectional view, with parts in elevation, taken along the line VII—VII of Figure 6 and illustrating one of the gate valves controlling flow from the stock spreader chamber to the stock inlet chamber.

Figure 8 is a horizontal cross-sectional view, with parts in elevation, taken along the line VIII—VIII of Figure 3.

Figure 9 is an end elevational detail view taken along the line IX—IX of Figure 4.

Figure 10 is a vertical cross-sectional view, with parts in elevation, taken along the line X—X of Figure 3.

Figure 11 is a horizontal cross-sectional view taken along the line XI—XI of Figure 10.

As shown on the drawings:

As shown in Figures 1 to 6 inclusive, the reference numeral 10 designates generally the stock inlet of this invention. The stock inlet 10, in the arrangement of Figure 1, receives stock from a delivery pipe 11 extending through the flooring F on which the inlet 10 is mounted. Excess stock from the inlet 10 is returned through a stock return pipe 12. The inlet 10 is mounted on the flooring F immediately in advance of the breast roll 13 of a Fourdrinier type paper making machine. As is conventional in such machines a forming wire 14 is trained around the breast roll and has an upper run providing a paper forming surface receiving stock from the inlet.

In the arrangement of Figure 1 a stock chest 15 is mounted at a level beneath the paper machine inlet 10 as, for example, in the basement. A pump 16 propels stock from the chest 15 through the delivery pipe 11 to the inlet. The stock return pipe 12 discharges back to the stock chest 15. As will be hereinafter more fully de-

scribed, whenever the pump 16 is stopped, all of the stock in the inlet 10 will be drained back through the delivery pipe 11 to the chest 15. In this arrangement, therefore, the inlet is self-draining and wastage of stock in the inlet whenever a shut-down occurs is eliminated.

In the arrangement of Figure 2 the stock chest 15 is mounted at a level beneath the inlet 10 as in Figure 1, but the pump 16, instead of propelling stock direct to the delivery pipe 11, forces the stock through a pipe 17 into a screen trough 18 mounted at a level above the inlet 10. Stock from the trough 18 then flows by gravity downwardly through the delivery pipe 11 to the inlet 10.

In both Figures 1 and 2 the amount of stock delivered to the inlet is regulated by the speed of the pump 16. In the arrangement of Figure 1 the pressure of the stock in the inlet is controlled by the speed of the pump, while in the arrangement of Figure 2 the pressure of the stock in the inlet is controlled by the hydraulic head of stock above the inlet. In the arrangement of Figure 1 the chest 15 preferably receives screened pulp, whereas, in the arrangement of Figure 2, the chest 15 can receive unscreened stock and the trough 18 will screen the stock before it is delivered to the inlet 10.

The inlet 10 has a bypass valve indicated generally by the reference numeral 19 associated therewith interposed between the inlet, the stock delivery pipe 11 and stock return pipe 12 for the purpose of diverting stock from the pipe 11 to the pipe 12. In the arrangement of Figure 1 this valve 19 is used in vertical position, whereas, in the arrangement of Figure 2 the valve 19 is used in horizontal position.

The valve includes, in the arrangement of Figures 1, 3 to 6, and 8, an open ended cylindrical casing 20 mounted vertically and having the bottom open end joined to the stock delivery pipe 11 and the top open end detachably connected to the intake pipe 21 of the inlet 10 through swing bolts 22. The casing 20 also has a side opening 23 communicating through an elbow pipe 24 with the stock return pipe 12.

An open ended cylindrical sleeve 25 is rotatably mounted in the casing 20 and has the interior thereof freely communicating with the open ends of the casing. This sleeve 25 has an intermediate cut-out portion 26 in the side wall thereof adapted to be placed into and out of communication with the opening 23 of the casing for diverting stock in regulated amounts from the pipe 11 to the pipe 12.

The sleeve 25 has a ring gear 27 secured therearound adjacent the upper end thereof to provide a ring of teeth meshing with a worm 28, as best shown in Figure 8, on a shaft 29 rotatably carried in the casing 20 and projecting outwardly from the casing. A readily accessible hand wheel 30 is mounted on the shaft 29 to rotate the sleeve 25 and thereby control the position of the cut-out portion 26 thereof relative to the outlet 23. Obviously, of course, the teeth 27 could be formed integrally with the sleeve 25.

By control of the position of the cut-out portion 26 of the sleeve, a continual flow of stock can be maintained through the delivery pipe 11 even though the inlet 10 will not accommodate all of this stock since excess stock can be diverted back through the return pipe 12 to the chest 15. A continual circulation and recirculation of stock can thus be maintained. Whenever a shutdown occurs, the stock in the inlet 10 automati-

cally drains by gravity back through the pump 16 to the chest 15, since the open ended sleeve 25 will not impede back drainage of stock.

In the valve 19 of Figure 2 a somewhat different casing 31 is used. This casing 31 is a horizontal cylinder with a closed end wall 32 at one end thereof and an open end communicating with the stock delivery pipe 11. An outlet 33 is provided in the casing 31 at the bottom thereof communicating with the stock return pipe 12 and a second outlet 34 is provided in the top of the casing communicating with the intake 21 of the inlet 10.

A cylindrical sleeve 35 is rotatably mounted in the casing 31 and has the gear teeth 27 thereon the same as the sleeve 25. However, the sleeve 35 only has an open end 36 communicating with the delivery pipe 11 and a curved closed end 37 for directing stock to the cut-out portion 38 in the side wall thereof. This cut-out portion 38 can communicate with either the outlet 33 or the outlet 34 and thereby stock from the delivery pipe 11 can be diverted from the intake 21 to the return pipe 12.

The inlet 10 includes a stock spreader chamber composed of a horizontal closed ended pipe 40 carrying the intake 21 on the bottom thereof midway between the closed ends thereof. The pipe 40 is equipped with mounting pads 41 near the ends thereof and depending from the bottom thereof.

Brackets 42 are carried by the pipe 40 and project forwardly therefrom toward and preferably over the breast roll 13 of the paper machine. Platform carrying pads 43 are provided on the top of the pipe 40.

The function of the pipe 40 is to receive the stock from the intake 21 and spread it across the width of the paper machine forming wire 14. The pipe 40 also forms the principal supporting or carrying member for most of the component parts of the inlet 10.

An outlet 44 is formed on top of the pipe 40 above the intake 21 and discharges through a gate valve casing 45 into an elbow pipe 46 carrying a vertical pipe 47 which is detachably connected through swing bolts 48 with an inlet connection 49 of the elbow 24. As shown in Figure 1, the casing 45 slidably mounts a gate valve 45a which can be raised and lowered by means of a hand wheel 45b.

In the arrangement of Figure 2 the pipe 47 is connected through an elbow 24a with the outlet 33 of the valve casing 31.

This arrangement of an outlet controlled by a valve at the top of the pipe 40 permits controlled circulation of stock from the spreader chamber back to the stock return pipe 12.

A plurality of outlet pipes 50 extend laterally forward from the top portion of the pipe 40 at spaced intervals along the length thereof. Six such pipes 50 are shown, but any number can be used in accordance with this invention depending upon the length of the pipe 40. Each of these outlet pipes 50 discharge through a gate valve casing 51. As shown in Figure 7, each gate valve casing 51 slidably supports a gate valve 51a with a cut-out bottom section 51b so that the valve can never be completely closed. A hand wheel 51c controls the position of each gate valve 51a.

A stock inlet chamber provided by a second horizontal closed ended pipe 52 has resting pads 53 extending from the bottom thereof mounted on top of the brackets 42. Inlet pipes 54 project laterally rearward from the bottom portion

of the pipe 52 and are each secured to a valve casing 55. Stock from the pipe 40 flows out of the top of this pipe laterally forward into the bottom of the pipe 52 and regulation of the valves 51a can be effected to uniformly distribute stock from the pipe 40 along the entire length of the pipe 52.

As shown in Figures 3 and 4, the pipe 52 has the ends thereof closed by end plates or caps 55.

10 As shown in Figures 1, 2, 5 and 6, a horizontal slot 56 is cut in the forward face of the pipe 52 near the bottom thereof. This slot 56 extends for the full length of the pipe 52 between the end plates 55.

15 A flow evener roll composed of a reticular tube 57 is mounted in the pipe 52 in front of the slot 56 on axles 58 which are rotatably supported in bearing supports provided by the end plates 55. As shown in Figures 3 and 4 an axle portion 58 projects beyond an end cap 55 and is coupled to the drive shaft 59 of a gear box 60 carried on a bracket 61 by the end plate 55. This gear unit can be driven to rotate the tube 57. The tube will break up fiber bundles and prevent undesirable eddy currents of stock in the pipe 52.

20 Baffles 62, as shown in Figures 4 to 6, extend upwardly from the bottom of the pipe 52 in front of each inlet pipe 54 to prevent streams of stock from the pipes 54 from flowing directly through the slot 56.

25 The inlet chamber provided by the pipe 52 is operative to further spread the flow of stock from the pipes 50 across the full width of the forming wire 14 and to kill any eddy currents of stock as well as to keep all of the stock continually in motion.

30 An inlet nozzle directs stock from the slot 56 onto the upper run of the forming wire 14 and is composed of a fixed lower lip 63 attached to the pipe 52 and extending from the lower edge of the slot 56 downwardly and forwardly to the upper run of the forming wire 14 as best shown in Figures 5 and 6. A fixed upper lip 64 is attached to the pipe 52 and extends forwardly and downwardly from the upper edge of the slot 56.

35 A plurality of upstanding ribs 65 are formed at spaced intervals on the lip 64 and each of these ribs has a pivot 66 supporting a crank or lever 67 intermediate the ends of the lever.

40 The lower ends of the levers 67 are pivotally connected through brackets 68 to an adjustable upper lip portion 69 which is connected to the upper lip portion 64 by means of a flexible strip 55 70.

45 The upper ends of the levers 67 are pivotally connected to trunnion blocks 71 each positioned between a pair of hand wheels 72, threaded on a rod 73. Each rod 73 is pivoted to an ear or lever 60 74 on a shaft 75 which is rotatably carried in bearing blocks 76 on the pipe 52.

50 As shown in Figure 4, a large number of threaded rods 73, hand wheels 72 and lever-operating trunnion blocks 71 are provided in closely spaced relation along the entire length of the pipe 52. The shaft 75 projects beyond the end plate 55 opposite that plate which carries the gear unit 60 and, as best shown in Figure 9, a gear sector 77 is secured on the end of the shaft 70 75 in front of the end plate 55. The sector 77 is in meshed engagement with a worm 78 on a shaft 79 rotatably mounted in bearing bosses 80 carried by the end plate 55. A hand wheel 81 is conveniently available on the shaft 79 for rotation of the sector 77 and shaft 75. The sector 77

can have indicia thereon cooperating with a pointer P on the end plate 55 indicating the position of the shaft 75 and thus indicating the nozzle opening.

Rotation of the hand wheel 81 will, of course, rotate the shaft 75 to move all of the rods 73 and thereby simultaneously tilt all of the levers or cranks 67 for raising or lowering the lip section 69 . The discharge orifice of the nozzle is thus conveniently controlled from a single point. The hand wheels 72 can be individually manipulated to slide the trunnion blocks 71 on their rods 73 to control the positions of increments of the lip section 69 along the length thereof. The position of the inlet nozzle is thus controlled along its entire length by a single means and is selectively controlled at closely spaced intervals along its length by manipulation of individual hand wheels 72 .

A standpipe 82 open at the top thereof extends from the top of the pipe 52 preferably near one end thereof and serves as an air vent for the inlet chamber. The pipe can be transparent to indicate the hydrostatic head pressure in the chamber.

As shown in Figures 3 to 6, the top pads 43 on the pipe 40 support side rails 83 which carry a floor 84 across the top of the pipe. This floor can be composed of boards, expanded metal grating or the like.

As best shown in Figure 3, the rear side rail 83 has brackets 84 thereon supporting a vertical railing 85 .

As best shown in Figures 5 and 6, brackets 86 are also formed on the pipe 52 and carry a second vertical railing 87 . The railings 85 and 87 are connected at one end of the inlet by a railing 88 . The walk 84 is thus surrounded by a railing. A ladder 89 supported by the side rails 83 extends downwardly from the end of the walk 84 opposite the railing 88 end thereof. This ladder gives convenient access from the floor level to the walk 84 .

An operator can readily reach all of the controls such as the hand wheels 81 , $51c$, $45b$, and 72 from the walk or ladder. The hand wheel 30 is conveniently reached from the floor level.

As best shown in Figure 3, the mounting pads 41 of the inlet are supported on end frames or stands 90 .

As best shown in Figures 10 and 11 each stand 90 has a central cylindrical well 91 slidably receiving a piston 92 acting at its upper end on the pad 41 . The cylindrical well 91 has a somewhat enlarged closed bottomed chamber 93 adapted to receive fluid under pressure from an inlet 94 . Fluid introduced into this chamber 93 will act on the end of the piston 92 to raise the same in the well 91 .

Each stand 90 has a bearing bracket 95 secured thereon and rotatably supporting an equalizer shaft 96 . Cranks 97 are secured to the equalizer shaft 96 adjacent each stand 90 and the ends of these cranks 97 are pivoted to links 98 . The links 98 in turn are pivotally connected to brackets 99 secured on the pipe 40 .

When it is desired to raise the entire inlet 10 for the purpose of changing the forming wire 14 of the paper machine, the swing bolts 22 and 48 are loosened and swung to out of the way positions as shown in Figure 6. Nuts 100 (Fig. 10) connecting the pads 41 with the stands 90 are removed, and the chambers 93 in the stands are subjected to fluid pressure such as hydraulic pressure for acting on the pistons 92 thereby rais-

ing the pistons and lifting the entire inlet as shown in Figure 6. The equalizer shaft 96 prevents one piston 92 from working ahead of the other piston since such operation will tend to tilt the pipe 40 thereby subjecting the shaft 96 to torsion. The shaft 96 , together with its links and cranks, thus ties both pistons together for uniform movement.

Upon completion of the wire change the hydraulic pressure is relieved and the pistons will drop by gravity toward the bottoms of their wells thereby again seating the intake pipe 21 on the valve casing 20 and also seating the pipe 47 on the pipe 49 . The swing bolts are then moved to the position shown in Figure 5 and the unit is again ready for operation.

As shown in Figures 5 and 6, a white water deflector 101 is provided under the upper run of the forming wire 14 immediately adjacent the breast roll 13 .

This deflector guides white water from the upper run of the wire and prevents the same from splashing on the breast roll. A plurality of wire supporting bars 102 are carried by the deflector in spaced parallel relation to carry the upper run of the wire between the breast roll 13 and the first table roll 103 . These bars 102 and the walls 104 of the deflector on which they are carried have beveled or undercut front edges 105 so that white water will not pile up under the wire adjacent these edges thereby increasing the drainage capacity of the water deflector.

From the above descriptions it will be understood that the inlets of this invention are supported on end frames or stands and are equipped with fluid pressure raising devices. The inlets have stock spreader chambers with central intakes which are detachably coupled to by-pass valve casings. The by-pass valves divert stock from a delivery pipe back to a storage reservoir thereby making possible a continual circulation of stock. The spreader chambers of the inlets can also be equipped with by-pass return passages for very accurate regulation of stock delivery from the inlet.

The spreader chamber discharges at intervals along its length into an inlet chamber which is mounted above the breast roll end of a Fourdrinier type paper making machine and which discharges along its entire length onto the upper run of the forming wire of such a machine. A readily controlled nozzle extends from the inlet chamber to direct the stock onto the wire.

Flow of stock from the spreader chamber to the inlet chamber can be carefully regulated and controlled by means of a plurality of gate valves so that the stock is uniformly distributed across the entire width of the paper machine.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A stock inlet for a Fourdrinier type paper making machine comprising spaced opposed end frames adapted to be mounted immediately in advance of the breast roll end of a Fourdrinier paper making machine, a first substantially horizontal stock conduit supported on said frames, a substantially vertical intake pipe communicating with the central bottom portion of said first conduit, a stock feed pipe, a stock discharge pipe, a valve casing between said pipes and said intake

pipe, a valve in said casing adapted to connect said intake pipe with said feed pipe and said feed pipe with said discharge pipe, means detachably connecting said valve casing and said intake pipe, a valved overflow pipe communicating with said first conduit, means detachably connecting said overflow pipe with said discharge pipe, a second substantially horizontal conduit supported by said frames, a plurality of valved connecting pipes spaced along the lengths of the first and second conduits and joining said conduits, a nozzle projecting from said second conduit having a discharge end over the breast roll end of the paper machine, said nozzle communicating with said second horizontal conduit along the length thereof, an adjustable upper lip on said nozzle, means for moving said upper lip along the entire length thereof, means interposed between said moving means and said lip for raising and lowering increments of said lip along the length thereof, and a hydraulic lift for raising and lowering the conduits relative to said end frames.

2. In a Fourdrinier type paper making machine having a forming wire trained around a breast roll to provide a web-forming surface along the upper run thereof, a stock inlet which comprises a first pipe, means mounting said pipe horizontally across the width of said machine in advance of the breast roll thereof, means for feeding stock to the central portion of said first pipe, a second pipe, means mounting said second pipe horizontally across the width of said machine above the web-forming surface thereof, said second pipe having an outlet along the length thereof for discharging stock onto the forming surface across the width thereof, and a plurality of valved conduits connecting said first and second pipes for uniformly distributing stock from the first pipe along the length of the second pipe.

3. Stock delivery apparatus for a paper making machine comprising a stock chest, a stock delivery pipe extending upwardly from said chest, a pump for propelling stock from said chest through said delivery pipe, a valve casing having an open ended valve sleeve receiving stock from said delivery pipe, said sleeve having a cut-out portion in the side wall thereof, a stock return pipe extending downwardly from said valve casing to said stock chest, means for rotating said sleeve to divert stock from the delivery pipe to said return pipe, an intake pipe receiving stock from the upper end of said sleeve, means defining a stock spreading chamber communicating with said intake pipe, means defining a stock inlet chamber having an elongated discharge orifice, and valved conduits connecting said spreader chamber with said inlet chamber to uniformly distribute stock from the spreader chamber along the length of said inlet chamber, said inlet chamber and said spreader chamber being arranged for automatic gravity drainage through said valve sleeve and said delivery pipe into said stock chest whenever said pump is inoperative.

4. Stock delivery apparatus for a paper making machine comprising a stock chest, an elevated stock reservoir, means for pumping stock from said chest to said elevated reservoir, a valve casing, a sleeve rotatably mounted in said valve casing, a stock delivery pipe connecting said elevated reservoir with the interior of said valve sleeve, said valve casing having top and bottom outlets, a stock return pipe joining said bottom outlet with said stock chest, an intake pipe communicating with said top outlet, said valve sleeve

adapted to connect said stock delivery pipe with said stock return pipe or with said intake pipe means defining a stock spreader chamber receiving stock from said intake pipe, means defining a stock inlet chamber having a discharge orifice along the length thereof, and a plurality of valved passages connecting said stock spreader chamber and said inlet chamber for uniform distribution of stock from the spreader chamber along the length of the inlet chamber.

5. A stock inlet for a paper making machine comprising a first closed ended pipe having a depending central intake, a valve casing detachably connected to said intake, a stock delivery pipe communicating with said casing, a stock return pipe communicating with said casing, a valve in said casing connecting said delivery pipe with said intake and adapted to selectively connect said stock delivery pipe with said stock return pipe, a plurality of valved pipes extending laterally along the length of said first pipe, a second pipe in spaced parallel relation with said first pipe communicating along its length with said valved pipes, said second pipe being at a higher level than said first pipe for gravity drainage into the first pipe, a discharge nozzle communicating with said second pipe along the length thereof and projecting laterally therefrom, and means for raising and lowering said first and second pipes, said valved pipes, and said intake toward and away from said valve casing.

6. A stock inlet for a paper making machine comprising an elongated closed ended pipe, mounting pads depending from said pipe, a stock intake conduit depending from said pipe, brackets extending laterally from said pipe, stands supporting said mounting pads to hold said pipe in horizontal position, lifting devices interposed between said stands and said mounting pads for raising said pipe, a second pipe mounted on said brackets, and valved conduits connecting said first and second pipes, said second pipe having an elongated discharge orifice along the length thereof whereby stock supplied through said intake will be spread in said first mentioned pipe to flow through said valved conduits in regulated amounts for uniform distribution to said second pipe and subsequent ejection from said second pipe along the length thereof.

50 7. In a stock inlet a conduit pipe adapted to extend transversely across the width of a Fourdrinier type paper making machine, a nozzle extending from said pipe having a fixed lower lip, a fixed upper lip section and a movable upper lip section hingedly connected to said fixed upper lip section, levers pivoted intermediate their ends to said fixed upper lip section, means pivotally connecting the lower ends of said levers to said movable lip section, a shaft extending along the length of said pipe, means on said pipe rotatably mounting said shaft, levers on said shaft, threaded rods pivoted to said levers, trunnion blocks slidably mounted on said rods, each of said trunnion blocks being pivoted to the upper end of a lever, hand wheels threaded on each rod for shifting said trunnion blocks, and means for rotating said shaft whereby said movable lip section can be simultaneously raised and lowered along the entire length thereof by rotation of said shaft and whereby selected increments along the length of said movable lip section can be raised or lowered independently of other increments of the lip section by manipulation of said hand wheels.

70 8. In a stock inlet for a paper making machine

a pair of end frames each having a well portion, a piston slidably mounted in each well portion, a stock inlet mounted on said pistons, a shaft rotatably supported on said end frames, cranks secured to said shaft, links connecting said cranks with said stock inlet, and means for introducing fluid under pressure to said wells under said pistons for raising said inlet, said shaft being twisted whenever one of said pistons works ahead of the other of said pistons to hold the pistons at the same level and thereby prevent tilting of the inlet.

9. A stock inlet for a paper making machine comprising a first horizontal pipe providing a stock spreading chamber, end frames supporting said pipe, a second horizontal pipe providing a stock inlet chamber, valved conduits connecting said first and second pipes, brackets carrying said second pipe from said first pipe, and hydraulic lift devices interposed between said end frames and said first pipe for raising and lowering the pipes and conduits.

10. In a stock inlet for a paper machine comprising a stock intake pipe, a stock delivery pipe, a stock return pipe, a valve casing connected to all of said pipes, a rotatable valve sleeve in said casing connecting said stock delivery and intake pipes, said sleeve having an opening in the side wall thereof, and means for rotating said sleeve to place said opening into and out of communication with the stock return pipe.

11. A stock inlet for a paper making machine, frames supporting said inlet, a piston slidable in each frame to raise the inlet above the frames, a shaft rotatably mounted on said frames, and spaced means connecting said inlet and shaft to rotate the shaft whenever the inlet is raised and lowered to twist the shaft whenever one piston works ahead of another piston.

12. A stock inlet for a Fourdrinier type paper making machine having a forming wire providing a web-forming surface which comprises, first and second horizontal stock conduit pipes adapted to extend transversely across the width of the forming wire, a feed pipe communicating with the first conduit pipe, said second conduit pipe having a slot outlet along the length thereof, a nozzle connecting said slot outlet with the forming surface provided by the forming wire, means spaced along the lengths of the conduit pipes connecting the

conduit pipes in fluid flow relation, flow control devices cooperating with said means to regulate amounts of fluid flowing through said means, and an individual adjusting mechanism for each device adapted to position the device for distribution of stock from the first conduit pipe uniformly along the length of the second conduit pipe to be ejected through the nozzle directly onto the forming surface of said forming wire.

13. In a stock conduit for a paper making machine having a forming surface, a first horizontal pipe arranged to extend transversely across the width of a paper making machine for defining a stock-spreading chamber, a second horizontal pipe in spaced lateral relation with said first pipe at a level slightly above the level of the first pipe but with the lower portion thereof overlapping the upper portion of the first pipe, said second pipe having a discharge nozzle along the length thereof arranged for directly discharging stock onto the forming surface of the paper making machine, and valved horizontal conduits connecting the top portion of the first pipe with the bottom portion of the second pipe at spaced intervals along the lengths thereof whereby stock introduced into the first pipe is spread across the width of the paper making machine and then distributed uniformly along the length of the second pipe for ejection through the nozzle directly onto the forming surface of the paper making machine with the second pipe providing a chamber above the level of the forming surface to insure flow of stock onto the forming surface.

14. In a stock inlet for a paper making machine, a stock distributing pipe arranged to extend transversely across the width of the paper making machine, a control valve comprising an open-ended casing having one end communicating with said stock distributing pipe, an open-ended sleeve rotatably mounted in said casing and accommodating flow of stock therethrough, said casing having an opening in the side wall thereof, said sleeve having a cut-out portion in the side wall arranged to register with said opening in the casing, and means for rotating said sleeve to selectively position the cut-out portion thereof relative to said opening.
